OIL PROSPECTING METHOD

William J. Sweeney, Summit, N. J., assignor to
Standard Oil Development Company, a corpora-
tion of Delaware

No Drawing. Original application December 14,
1937, Serial No. 179,676. Divided and this ap-
plication August 9, 1941, Serial No. 406,220

3 Claims. (Cl. 23—230)

1

The present invention is directed to a method for prospecting for oil and particularly to the type of method in which near surface gases are analyzed for constituents indicative of petroleum origin.

According to the present invention samples of near surface gases are obtained by collecting spaced samples of adsorbent material which have been exposed to such gases in their native environment and recovering the gas from said adsorbent material by desorption. This adsorbent material may be naturally occurring material or adsorbent material which is planted for the purpose at spaced points over the area to be explored.

One aspect of the present invention resides in a particular method for desorbing the adsorbent material involving the steps of chilling the material to a temperature below that of the lowest boiling constituent sought for, subjecting the sample to evacuation for a period sufficient to purge the samples of constituents boiling below the boiling point of that desired and then raising the temperature of the sample to a level above the boiling point of the constituent or constituents desired while continuing the evacuation and collecting the gases liberated during this period.

It is an object of the present invention to provide a method for detecting the presence of and measuring these hydrocarbons in gas mixtures in which they are present in amounts as small as one part in a million. Generally, the gas mixtures examined for the purpose of the present invention will contain ethane and higher hydrocarbons in an amount of at least ten parts in a million and this concentration has significance in establishing the presence of petroleum deposits beneath the surface at which the gas sample is connected. A suitable analytical method which may be used for this purpose is that described and claimed in Patent 2,170,435 issued September 24, 1940.

When prospecting for oil by the method of the present invention, the samples of soil gas may be procured by any one of a number of methods. One of these methods is to suck the gas from a hole in the ground sealed from the atmosphere. Another method is to place an adsorbent material, such as active carbon, in a borehole sealed from the atmosphere, leave it there for a sufficient time for it to become saturated with the hydrocarbons in the soil gas and then withdraw it and recover the adsorbed hydrocarbons by evacuation or by treatment with steam or inert gas.

For the purpose of the present invention it is

preferable to secure the sample of soil gas by removal of adsorbed gases from the soil itself. This removal can be accomplished by any of the known methods referred to above. The samples of gas so obtained are much richer in hydrocarbons than samples obtained by mere suction from a borehole, since the latter are contaminated with large quantities of air. A novel procedure for obtaining an excellent sample is to

5 place a sample of soil in a suitable container, evacuate the container to draw off water and adsorbed gases, pass the recovered gases through a train of adsorbing media for the removal therefrom of water vapor and carbon dioxide and 10 compress the purified sample into a previously evacuated absorption cell which is then directly examined in the spectroscope. It is advantageous in some cases to heat the soil sample during evacuation.

20 Another method for procuring a sample contemplated by the present invention is to place a sample of soil in a suitable container chilled to such a point that methane only is removed under vacuum and subject it to evacuation. This 25 operation will remove any adsorbed methane from the soil. When no more gas is recovered by evacuation at this temperature the temperature of the container can be raised to the boiling point of ethane and the evacuation repeated. If 30 desired this procedure can be repeated for the recovery of propane and butane. The procedure can be simplified to suit the purpose of locating oil by following the methane removal step with an evacuation at the temperature of boiling propane or butane as desired. In the latter case, ethane, propane and butane will be recovered. The sample recovered at this temperature must 35 be subjected to dehydration before being examined in the spectroscope.

40 Some of the diluent effect of the methane can be avoided without resorting to refrigeration by collecting the soil sample at a depth adjacent to the uppermost water-table. This will usually be at least twenty feet below the surface of the 45 ground and may be as deep as sixty feet. In this zone there is a tendency for the soil to adsorb higher hydrocarbons such as propane and butane to the exclusion of methane. With such a sample it may be possible to identify propane and/or 50 butane by simply heating the sample and collecting and condensing the evolved vapors. Any condensable quantity of propane or higher hydrocarbon contained in such a sample is direct evidence of the existence of an oil deposit at 55 a lower level.

Other methods for obtaining a sample of soil gas include the evacuation or steaming of cores of soil obtained while drilling, boiling large bodies of stagnant water, boiling samples of sub-surface water obtained in the area to be explored, and boiling or steaming samples of drilling mud used in the drilling of a well in the neighborhood under investigation. Still another method is to bore a hole in the ground, seal the top of the hole from the atmosphere, run a pipe through the seal to the bottom of the hole, feed in carbon dioxide, steam or other absorbable gas through this pipe and draw out gas from the hole through another pipe in the seal. The gases so recovered are passed through absorbing agents for carbon dioxide and water and the remaining permanent gases are utilized for examination according to the method of the present invention.

This application is a division of my copending application Serial No. 179,676, filed Dec. 14, 1937 and entitled Oil prospecting method, now abandoned.

The nature and objects of the present invention having been thus described and illustrated, what is claimed as new and useful and is desired to be secured by Letters Patent is:

1. In a method for locating subterranean deposits of petroleum by collecting samples of soil gas and analyzing them for significant constituents, the step of collecting a gas sample which comprises exposing an adsorbent to soil gas in its native environment for a period of time sufficient for adsorption of said gas and then recovering a gas sample from the adsorbent by desorption.

2. A method of geochemical oil prospecting comprising sinking a bore, disposing an adsorbent for hydro-carbon gases therein in such relation to said bore that the gases in said bore have access to the adsorbent, removing said adsorbent and analyzing the gases adsorbed for the presence of significant gases.

3. A method of geochemical oil prospecting comprising sinking a bore, disposing an active carbon therein in such relation to said bore that the gases in said bore have access to the active carbon, removing said active carbon and analyzing gases adsorbed thereby for the presence of significant gases.
